UNITED STATES PATENT OFFICE.

ROBERT CUMMING ANNAND, OF SOUTH SHIELDS, ENGLAND.

PERFORATOR FOR WEB-PRINTING MACHINES.

SPECIFICATION forming part of Letters Patent No. 634,255, dated October 3, 1899.

Application filed January 18, 1899. Serial No. 702,516. (No model.)

To all whom it may concern:

Be it known that I, ROBERT CUMMING ANNAND, of South Shields, England, have invented certain new and useful Improvements in 5 the Perforator Mechanism of Web-Printing Machines, of which the following is a specification.

My invention relates to the perforator mechanism used in web-printing machines for severing the web of paper into sheets while it is passing through the machine.

The usual means employed to perforate or sever a web of paper into sheets consists of a pair of rotating rolls, one of which carries the severing perforator-blade and the other has a longitudinal groove into which the perforator-blade passes at the moment of cutting off the sheet.

The perforator-blade is carried in a frame 20 which is fastened into a longitudinal slot in the cylinder. There are usually two yielding pieces, generally called "buffers," one on each side of the perforator-blade, which serve to press and hold the sheet against the opposite cylinder while the perforator-blade is forced through the paper and into the slot in the opposite cylinder. Spiral springs are usually employed to force out these buffers at each side of the perforator-blade, and they 25 are prevented from coming out altogether by means of pins put through the perforator-frame, there being corresponding slots in the buffers through which the pins pass. The springs are objectionable, as they are apt to break, and loose pieces of the springs are 30 therefore liable to get about the sides of the buffers and jam them. The pins are also objectionable, because of the necessity of having slots and holes in the perforator-frame, the buffers, and the perforator-blade, and when 35 it is necessary to put in a new blade these several details cause delay.

According to my invention I employ rubber disks to force out the buffers. I also form 40 a lip or inturned flange on the outer part of each half of the perforator-frame. Corresponding with this lip there is a shoulder on the buffer, and this shoulder by coming 45 against the lip effectually prevents the buffers from escaping.

In the accompanying drawings, Figure 1 is a longitudinal elevation of perforator mech-

anism constructed according to this invention. Fig. 2 is a section on the line A B of Fig. 1. Fig. 3 is an elevation of the end C, 55 Fig. 1.

a a a represent the perforator-frame.

b is the perforator-blade, the edge of which is serrated, as usual.

c c are the buffers, made, preferably, of hard 60 wood.

d d are the rubber disks.

The perforator-frame is made in halves secured together by bolts *ff*, as shown. The perforator-blade is held rigidly in position by 65 being clamped between the halves. For convenience the buffers are in sections, as seen in Fig. 1. One of the rubber disks is placed at each end of the sections in a recess *g* in the lower part of the perforator-frame *a*. To 70 make the disks more elastic, I form them with a hole *h* in the center.

e e are lips or inturned flanges at the sides of the perforator-frame, and *k k* are shoulders on the buffers *c*, engaging with the said lips, 75 so as to form a rigid stop to prevent the buffers rising farther than required.

The buffers *c c* have each a hollow *i* at the middle of their inner face to keep the rubber disks *d d* in a central position and prevent 80 them rubbing on the perforator-frame *a* or perforator *b*, and thereby damaging and shortening the life of the rubbers.

The construction of perforator hereinbefore described is simpler than what has hitherto 85 been used, the rubber disks or the buffers can be more quickly renewed in case of wear, the risk of injury from broken springs is avoided, and there is less risk of the buffers getting out of the holder than in cases where 90 they are held in position by means of pins passing through slots in the wood.

What I claim, and desire to secure by Letters Patent, is—

1. In perforator mechanism of web-printing machines, the combination with the buffers or yielding pieces at each side of the perforator-blade of rubber disks in the perforator-frame, said disks pressing elastically against the inner face of said buffers, substantially as and for the purpose set forth. 95

2. In perforator mechanism of web-printing machines, the combination with a perforator-blade, of a perforator-frame having in-

turned flanges at its outer edges, buffers or yielding pieces at each side of the perforator-blade and having shoulders engaging with said inturned flanges, and rubber disks in the perforator-frame bearing against the inner face of said buffers, whereby said buffers are pressed elastically outward by said disks and are prevented from escaping from said frame by said flanges and shoulders, substantially as set forth.

3. In perforator mechanism of web-printing machines, buffers or yielding pieces at each side of the perforator-blade, said buffers having hollows at the middle of their in-

ner face in combination with rubber disks in the perforator-frame, the upper portions of said disks entering said hollows and pressing elastically against the inner face of said buffers, substantially as and for the purpose set forth.

In witness whereof I have hereunto signed my name in the presence of two subscribing witnesses.

ROBERT CUMMING ANNAND.
